PUNCHING MACHINE

Edward J. Von Pein and Paul J. Schlessiger, Endicott, N. Y., assignors to International Business Machines Corporation, New York, N. Y., a corporation of New York

Application July 20, 1937, Serial No. 154,594

2 Claims. (Cl. 164—115)

This invention relates to punching or perforating machines and more particularly to machines of the type in which punching may be controlled either manually or by a previously punched record card.

The principal object of the invention is to increase the general flexibility and diversity of control of a card reproducing or perforating machine so that reproduction of certain data on a punched card may be effected in accordance with any desired arrangement. Where it has heretofore been desired to reproduce data in particular fields of a punched card and to suppress data punched in other fields, so-called skip bars and column cut-out bars have been provided to effect a machine setup whereby the same fields of each punched card to be reproduced would be rendered active and the same fields in each suppressed.

Generally, a reproducing machine comprises a card carriage in which a prepunched master card and a blank card are placed side by side for concurrent step by step advance, the former to pass a row of sensing brushes and the latter to pass a row of punches.

The sensing brushes read the data punched in the columns of the master card and control the operation of the punches to duplicate the perforations in the same columns of the blank card.

Where it has been desired to suppress the sensing of certain columns, mechanical cut-out bars have been provided to do this and a different bar is required for each different arrangement of columns to be cut out.

In accordance with the present invention, it is proposed to provide a universal electrical arrangement whereby through a simple plugboard manipulation, any column or columns may be cut-out and the arrangement rapidly changed.

Skip bars have been provided to cause the carriage to advance certain columns of the blank card past the row of punches where such columns are not to receive perforations. This also has necessitated a different removable bar for each different arrangement of columns to be skipped and it is also proposed to provide a universal electrical arrangement to enable any column or columns to be automatically skipped by a simple plug wire adjustment.

Further objects of the instant invention reside in any novel feature of construction or operation or novel combination of parts present in the embodiment of the invention described and shown in the accompanying drawings whether within or without the scope of the appended

claims and irrespective of other specific statements as to the scope of the invention contained herein.

In the drawings:

Fig. 1 is a wiring diagram of the electric circuits of the machine.

Fig. 2 is a detail of the essential operating elements of the punching section of the machine.

Fig. 3 is a detail of the card carriage escapement mechanism of the machine.

Fig. 4 is a detail of the punch controlling contact and the operating device therefor.

Fig. 5 is a detail in section of the punched or master card analyzing devices.

Fig. 6 is a detail of the circuit breaker device.

The punching machine is generally of the form shown in the U. S. patent to Lee and Phillips No. 1,772,186, granted August 5, 1930, as improved by F. L. Lee, No. 1,878,935, granted September 20, 1932, and by Lee and Daly No. 1,976,618, granted October 9, 1934, and the description thereof will be limited to the features essential to an understanding of the present invention.

In Fig. 2, punch selecting magnets 10 are provided, there being one for each of the twelve index point positions of the record card. Energization of magnet 10 will attract its armature to rock an arm 11 in a counter-clockwise direction about its pivot 12, thus moving key 13 downwardly to rock a bell crank 14 which has suitable connection with an interposer 15 mounted for horizontal reciprocation. The forward end of interposer 15 is suitably guided between an operating bar 16 and the upper end of a punch 17.

Forward movement of the interposer will position its widest portion between bar 16 and punch 17 so that subsequent counterclockwise rocking of bar 16 about pivot 18 will move the interposer and punch downwardly to perforate the record card 19. A notch 20 in the interposer cooperates with a bail 21 to rock the same in a counter-clockwise direction when the interposer is moved toward the left. Rocking of bail 21 in such manner will draw a hook-shaped member 22 (see Fig. 4) toward the left to close a pair of contacts 23.

As will be explained in connection with the circuit diagram, contacts 23 complete a circuit through the punch magnet 24, causing it to attract its armature 25 and through linkage 26 draw downwardly on the bar 16 to cause depression of the selected punch. Depression of key 13 may, of course, be effected independently of the operation of the magnet 10 for the purpose of manually controlling punching operations.

Disposed beneath the interposers 20 is a ball 21 which is carried by rod 28 upon one end of which is secured an arm 29 (see Fig. 3) for operating the escapement mechanism. This mechanism comprises a holding pawl 30 pivoted at 31 to the frame of the machine and a stepping pawl 32 loosely pivoted on rod 28 and normally urged by a spring 33 into engagement with the teeth 34 on the upper edge of the carriage rack 35. Rocking of rod 28 in a counterclockwise direction under action of an interposer 15 will lower pawl 30 into engagement with a tooth 34 to hold the rack 35 in position while punching is being effected. This action at the same time raises pawl 32 out of engagement with teeth 34 and by virtue of its loose connection with rod 28 will move slightly toward the right in readiness to intercept the next tooth 34 when the rod 28 is returned to its original position.

Referring to Fig. 1, the rack 35 is suitably mounted for horizontal movement in the frame of the machine and may be manually moved toward the right to the position shown wherein a record card 19 is placed in position with the first column thereof in line with the punches 17. A finger piece 36 pivoted on a cross arm 37 of the carriage is utilized to return the same toward the right. When this finger piece is engaged (see Fig. 6), it turns slightly about its pivot 38 before moving the carriage and through a depending projection 39 rocks a rod 40 to rotate rod 41. Rod 41 has a finger 42 cooperating with the blade of a pair of cut-out contacts 43. The arrangement is such that during the movement of the carriage toward the right contacts 43 are open and remain so until finger piece 36 is released.

In Fig. 1, gear teeth cut on the underside of the rack 35 cooperate with suitable gearing 44 which is connected to the usual spring barrel 45 and governor 46 which tend to move the rack toward the left at a regulated rate and which effect such movement under control of the escapement mechanism just described.

Rack 35 is provided with extensions or arms 37 and 47 between which a pattern or master card 48 is positioned in columnar alignment with the blank card 19 and which is adapted to be moved back and forth with the rack. An arm 49 carried by the rack 35 is provided for cooperation with the card 19 to move it column by column past the punches 17.

Positioned above the pattern card 48 is a contact roller 50 (see also Fig. 5) which is insulated from the frame of the machine and supported by a door 51 pivoted at 52. Directly below the roller 50 is a row of brushes 53 carried by a bar 54 which is normally in the position shown in Fig. 5, holding the brushes down out of engagement with the card 48. A magnet 55, upon energization, will attract its armature 56, actuating linkage 57 to cause upward movement of brushes 53 into engagement with the pattern card. This brush operating structure is fully shown and described in the U. S. Patent to Lee and Daly No. 1,976,618, granted October 9, 1934 to which reference may be had for further details of construction.

Referring to Figs. 1 and 3, beneath the pawl 32 lies the free end of a so-called skip-lift lever 59 which is pivoted at 60. For the purposes of the present invention, a rod 61 is arranged to abut the underside of lever 59 in line with pawl 32 and is suitably mounted for vertical reciprocation. The lower end of rod 61 rests upon an arm 75 of armature 62 so that when magnet 63 is ener-

gized, rod 61 will be elevated and will raise pawl 32 out of engagement with teeth 34 freeing the rack 35 for leftward movement. The rod 61 carries a collar 64 which latches over armature 65 of magnet 66 so that the rod when raised will remain up until magnet 66 is energized. The interval between the successive energization of magnets 63 and 66 will therefore determine the extent that rack 35 will advance uninterruptedly and it is apparent that by adjusting the speed of operation of the magnets and the rate of movement of rack 35, the carriage may advance one or more teeth.

The arrangement now to be described will enable the energization of magnet 63 when any selected column of card 19 is at the punches to initiate a skipping operation at such point and will subsequently enable the energization of magnet 66 at any later column of the card to terminate the skipping at that column.

Upon arm 47 is mounted a brush carrier 70 provided with electrically connected brushes 71 and 72, brush 71 being designed to cooperate with a common conducting strip 73 and the brushes 72 being designed to cooperate with eighty individual conducting blocks 74, there being one block for each of the eighty columns of the record cards. The strips 73 and blocks 74 are mounted in a block of insulating material 75 which is suitably secured to the frame of the machine. One of the brushes 72 is in contact with a block 74 corresponding to the column of the record under the punches 17 or in cooperation with the brushes 53. Each block 74 is electrically connected to a pair of plug sockets 76.

A group of sockets 77 is provided, any one of which, when connected by a plug wire 78 to a socket 76, will automatically cause the carriage to skip when the related column is in punching position.

A second group of sockets 79 is provided, any one of which, when connected by a plug wire 80 to a socket 76, will automatically terminate the skipping action when the related column is at the punching position.

A third group of sockets 81 is provided, any one of which, when connected by a plug wire 82 to a socket 76 will prevent sensing of the related column of the pattern card and one or more subsequent columns.

A fourth group of sockets 83 is provided, any one of which, when connected by a plug connection 84 to a socket 76 will re-enable the sensing of the pattern card when the related column is reached.

The complete operation of the machine will now be traced with particular reference to Fig. 1. It will be assumed for purposes of explanation that the card 19 is to be manually punched in columns 1 to 9; automatically skipped across column 10 and subsequent columns to present column 40 and then punched in columns 40 to 49 under control of the pattern card. It is assumed that the pattern card contains perforations in columns 50 to 59 which it is not desired to duplicate and it is desired to hand punch columns 60 to 80. For this setup the plug connections 78, 80, 82, and 84 are made as indicated in Fig. 1.

After cards 19 and 48 have been placed in position in the machine and the rack 35 moved toward the right to bring the first column of the card 19 into registration with the punches 17, switch 85 is closed to supply current to lines 86 and 87. A circuit is immediately completed from switch 85, line 86, cutout contacts 43, so-

called last column contacts 88 (which open after the last column is punched), contacts 89, brush 90, contact roller 50, brush 91, magnet 55, wire 92, line 87 to switch 85. This raises brushes 53 into engagement with pattern card 48. Since it is assumed that no perforations are in columns 1 to 9 of card 48, no circuits will be established through brushes 53.

Operation of keys 13 is now effected to punch 10 columns 1 to 9, one by one, each key depression being followed by a punch operation and subsequent escapement to the next column. As explained above, operation of any key 13 will cause closure of contacts 23, energizing magnet 24 to effect punching and escapement.

When the card 19 has escaped from column 9 to column 10, a circuit is completed which is traceable from switch 85, line 87, common strip 73, brushes 71, 72, block 74, socket 76 in column 10, connection 78, socket 77, wire 93, magnet 63, contacts 43 to switch 85. Magnet 63 elevates rod 61 to raise pawl 32 to free rack 35 for movement toward the left.

The carriage will now advance uninterruptedly 25 until column 40 is at the punching position. When it arrives in this position, a circuit is immediately established from switch 85, line 87, common strip 73, brushes 71, 72, block 74 in column 40, socket 76, connection 80, socket 79, wire 30 94, release magnet 66, contacts 43 to switch 85. Magnet 66 will release rod 61 and pawl 32 will interrupt the rack 35 with column 40 in punching position.

The pattern card 48 contains perforations in 35 column 40 and subsequent columns and automatic duplication of the data will now take place through circuits of which the following is representative. From switch 85, contacts 43, line 86, contacts 88, 89, brush 90, hole in column 40 of card 48, corresponding brush 53, wire in cable 95, punch selecting magnet 10, line 87, back to switch 85. Magnet 10 will advance its interposers and effect punching and escapement as described.

When the fiftieth card column is in punching 45 position a circuit is completed from switch 85, line 87, strip 73, brushes 71, 72, block 74 in column 50, socket 76, connection 82, socket 81, wire 96, magnet 97, wire 98, line 86, contacts 43 to switch 85. Magnet 97 will attract its armature 99 to open contacts 89 in the duplicating brush 50 circuits, thereby preventing completion of further circuits therethrough. When armature 99 is rocked counterclockwise, it is latched in such 55 position by armature 100 of magnet 101 and remains so until magnet 101 is energized.

The carriage is now stepped along by key operation until column 60 is reached when a circuit is traceable from switch 85, line 87, strip 73, brushes 71, 72, block 74 of column 60, socket 76, connection 84, socket 83, wire 102, magnet 101, wire 98, line 86, contacts 43 to switch 85. This releases contacts 89 for reclosure and from this point on punching is effected under control of perforations in card 48 or keys 13.

65 Punching in the last or eightieth column is ac-

companied by escapement slightly beyond the last column and such action opens contacts 88 to prevent circuits through brushes 53 and magnet 55. The punched card is removed from the machine and a new blank card inserted in the carriage. As the carriage is being returned to the left by engagement of the finger piece 36 (Fig. 6) contacts 43 are open, preventing the completion of any circuits as the brushes 71, 72 wipe over the blocks 74 and strip 73.

The sockets 77, 79, 81, and 83 are provided in multiple so that several fields of card 19 may be automatically skipped and sensing of several fields of card 48 may be suppressed and it is apparent that with sockets 76 multiplied the skipping and elimination may be co-extensive or overlap.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In apparatus for punching cards to record 30 data successively in different card fields, punching, duplicating means to control the punching in accordance with a pattern, means for moving said card step by step to successive positions, means comprising a single selectively settable device 35 positionable to cause suppression of duplicating operations in any desired position of the card and all succeeding positions and means comprising a further single selectively settable device positionable to reenable the suppressed 40 duplicating operations in any desired later position of the card and succeeding positions.

2. In a duplicating punching machine, a carriage arranged to receive a pattern card and a blank card to concurrently move the pattern card 45 column by column past a row of sensing devices as the blank card is moved column by column past a row of punching devices, said sensing devices being arranged to control said punching devices to duplicate perforations sensed in the pattern card, means for advancing said carriage, a selectively settable device, a member carried by said carriage and cooperating with said settable device, means controlled by said member and device when the carriage is in any selected position 50 for causing suppression of the operation of said sensing devices, or the initiation of an uninterrupted advance of said carriage or both and means controlled by said member and settable device when the carriage is in any selected position 55 for reenabling the operation of said sensing devices or the termination of the uninterrupted advance of said carriage or both.

EDWARD J. VON PEIN.

PAUL J. SCHLESSIGER.
